UNITED STATES PATENT OFFICE

JOHN MUCK, OF MILWAUKEE, WISCONSIN, ASSIGNOR OF ONE-HALF TO FRANK J. UIBEL, OF MILWAUKEE, WISCONSIN

FOUNTAIN PEN

Application filed December 16, 1926. Serial No. 155,137.

This invention relates to fountain pens.

It is an object of this invention to provide improved mechanism for filling a fountain pen with ink and for co-operating with the pen to feed the ink to the point thereof.

It is also an object of this invention to provide for fountain pens an improved pen designed to hold a quantity of ink and to prevent leakage when not in use.

10 In the drawings:

Figure 1 is a fragmentary longitudinal sectional view of a fountain pen casing showing the interior mechanism, a portion of which is broken away.

15 Figure 2 is a sectional view taken on the line 2—2 of Figure 1, the rubber bag being removed to more clearly show the operating mechanism.

Figure 3 is a plan view of the pen proper 20 shown in Figure 1.

Figure 4 is a sectional view taken on the line 4—4 of Figure 3.

Like parts are identified by the same reference characters throughout the several 25 views.

The fountain pen, embodying the invention disclosed herein, includes a barrel or casing 1, a pen cap 2, a compressible rubber ink bag 3 within the casing, and a pen 4.

30 The pen 4 is provided with a spoon portion 5 which is preferably soldered to the pen along a portion of the adjacent straight margins 6 of the pen and spoon portion. The spoon portion 5 is contoured along the margin 7 to conform to the contour of the adjacent portion of the pen 4. The margin 7 is not connected with the adjacent portion of the pen in order to permit the pen point to freely flex.

40 Thus a space is provided within the pen which may contain ink. The rear portion of the pen 4 and spoon portion 5 are positioned within an aperture 8 of the casing and a feed plug 9 having a feed opening 10 is inserted into the opening 8 to secure the pen in position. The pen is provided with the usual slit 12 and has lugs 13 bent outwardly to provide an aperture 14. The pen shank and associated 45 end of the spoon portion form a cylindrical

barrel which receives the lower end of the feed plug 9.

The feed plug 9 projects into the interior of the barrel or casing 1. Upon this projecting portion of the plug is secured the neck 15 of the compressible rubber casing or bag 3 within the outer casing 1. Lying adjacent the rubber bag is a rod 16 having axially offset portions 17 and 18. The offset portion 17 is provided with a slotted bearing 19 in the 60 tongue 20 projecting from the interior wall of casing 1. This bearing is eccentric to the axis of casing 1. The offset portion 17 projects through the tongue 20 and is provided with a lever or crank 21 which, in the position shown in Figure 1, is substantially concentric with the casing 1.

Offset portion 18 of the rod 16 is substantially aligned with portion 17, is in contact with the pen 4, and is provided with a bearing 70 at 22 in the casing 1. The offset portion 18, as shown in Figure 1, projects beyond the barrel or casing 1 and lies between the lugs 13 of the pen thereby to act as a valve for opening 14 in such pen.

75 The rear end of the casing 1 is provided with a cap 23 threaded to the casing for removal therefrom. This cap is provided upon its interior with a retaining cup 24 secured therein in any suitable manner, preferably by 80 press fitting to the interiorly projecting portion 25 of the cap 23. Retaining cup 24 is apertured axially of the cap 23 and the crank 21 of rod 16 extends through such aperture.

Within the cup 24 and upon crank 21 is 85 provided a washer 26 secured upon the crank in any suitable manner such as beaded end 27.

Attention is called to the manner in which the cap 2 is fitted to the casing 1. The casing is provided at its extreme end adjacent the 90 pen 4 with a thread 30, a shoulder 31 adjacent the inner end of thread 30, and a tapered portion 32 converging from the shoulder 31. Seated against the shoulder 31 is a rubber washer 33. The cap 2 is provided with a 95 threaded portion complementary to the thread 30, a shoulder complementary to the shoulder 31, and a tapered or beveled end complementary to the tapered portion 32. Thus when the cap 2 is secured to the casing 1, 100

as shown, the shoulder upon the cap abuts the washer 33 and thereby prevents any ink from flowing to the peripheral portion of casing ordinarily grasped during writing operations.

When it is desired to fill a fountain pen embodying this invention, the cap 23 will be removed by properly rotating it upon its threaded connection with the casing 1. After 10 the cap 23 has been removed from the casing 1, it may be used as a rotatable grip upon the crank 21. It will also be noted that the cap 23, when being removed from the casing, will, through the washer 26, beaded end 27 and 15 crank 21, cause the rod 16 to slide longitudinally of its bearings 19 and 22 and thereby withdraw the end of portion 18 from its position between lugs 13 of the pen 4.

Assuming that the cap 2 has been removed, 20 the pen 4 may then be immersed in ink of sufficient depth to cover the opening 14 in the pen. The compressible bag 3 may then be compressed by the rod 16 which will be oscillated about its bearings, such rotation being 25 accomplished through cap 23 and crank 21. Viewing Figure 2, it will be observed that rotation of the above mentioned compressing mechanism in a counterclockwise direction, will cause the bag or container 3 to be compressed and thereby force a substantial 30 amount of air in such bag to pass out through the feed opening 10 in plug 9 and aperture 14 in pen 4. The broken lines in Figure 2 indicate the position of the filling parts when 35 the bag is fully compressed. Thereupon the rod 16 may be rotated in a clockwise direction relative to Figure 2 by the mechanism previously described. The bag 3 will then return to its normal position indicated in Figure 1 and the suction caused by the return of 40 such bag to its normal position will draw the ink to the interior thereof through aperture 14 and opening 10.

When the pen has been supplied with ink 45 in the manner just described, the cap 23 may be threaded upon the casing 1 and thus cause the rod 16 to return to its position shown in Figure 1, thereby moving the end 18 of the rod to substantially close the opening 14. 50 The pen will then be ready for use.

In writing with the pen, pressure upon the nib will cause the divided portions thereof to leave the margin 7 of the spoon 5. This will permit ink within the cavity 11, formed by the spoon and pen, to flow, by capillary action, 55 along the margin 7 to the point. The nib, however, normally remains in contact with the margin 7 of the spoon and thereby keeps ink within the cavity 11 from flowing to the exterior.

I claim:

1. In a fountain pen, the combination with a casing, of a compressible ink container within said casing, a rod lying adjacent said container and slidably journaled in said casing

for axial movement, said rod having a crank arm extending exteriorly of said casing, and a cap for said casing normally concealing said arm and removable axially of the casing, said cap being rotatably connected with said arm and fixed against axial movement thereon, whereby when said cap is removed from said casing said rod will be moved axially. 70

2. In a fountain pen, the combination with a casing having a pen provided with an ink supply opening, of a compressible ink container communicating with said opening, a rod lying adjacent said container and journaled in said casing for sliding movement and for oscillatory movement about said journal, said rod having a portion normally closing said opening, and means for sliding and oscillating said rod, whereby said rod may be moved to open said opening and to compress said container. 75

3. In a fountain pen, the combination with a casing having a pen provided with an ink supply opening, of a compressible ink container communicating with said opening, a rod lying adjacent said container and journaled in said casing for sliding movement and for oscillatory movement about said journal, said rod having one end normally closing said opening and having the other end extended exteriorly of said casing, and a cap normally concealing the extended end and secured thereto, said cap being removably engageable with said casing, whereby said rod may be moved axially and oscillated about said journal. 90

4. In a fountain pen, the combination with a casing having a fountain pen provided with an ink supply opening, of a compressible ink container communicating with said opening, a rod lying adjacent said container and journaled in said casing for sliding movement and for oscillatory movement about said journal, said rod having one end normally closing said opening and having the other end provided with a crank exteriorly of said casing, and a cap normally concealing said crank and secured thereto, said cap being removably engageable with said casing, whereby when said cap is removed from said casing, said rod may be moved axially and oscillated about said journal. 100

5. In a fountain pen, the combination with a casing having a fountain pen provided with an ink supply opening, of a compressible ink container communicating with said opening, a rod lying adjacent said container and journaled in said casing for sliding movement and for oscillatory movement about said journal, said rod having one end normally closing said opening and having the other end provided with a crank exteriorly of said casing, and a cap normally concealing said crank and secured thereto for rotation thereon, said cap being threadably engageable with said casing. 120

6. In a fountain pen, the combination with
a casing having a pen provided with an ink
supply opening, of a compressible ink con-
tainer communicating with said opening, a
5 rod lying adjacent said container and slid-
ably journaled in said casing and oscillatable
about said journal, said rod having one end
normally closing said opening and having
the other end provided with a crank exter-
10 iorly of said casing, whereby said rod may be
moved axially and oscillated about said jour-
nal.

7. In a fountain pen, the combination with
a casing having a pen provided with an ink
15 supply opening, of a compressible ink con-
tainer communicating with said opening, a
rod lying adjacent said container and oscil-
latably journaled in said casing for oscil-
latory movement thereabout, said rod having
20 one end normally closing said opening and
having the other end provided with a crank,
whereby said rod may be oscillated.

8. In a fountain pen, the combination with
a barrel, of a compressible ink container in
25 said barrel, a pen point projecting from said
barrel and communicating with said con-
tainer; said pen comprising a pen point
proper provided with an opening, a spoon
having its margin normally contacting
30 throughout with the margin of said pen
proper, whereby to form an ink receiving
cavity within said pen communicating with
said container; and means for compressing
said container, said means normally closing
35 the opening in said pen proper and leaving
said opening unobstructed when said con-
tainer is under compression.

9. A pen point for a fountain pen pro-
vided with an aperture in its back a spoon
40 shaped ink holder, arranged with the pen
shank to form a generally cylindrical barrel,
a hollow pen holder provided with a centrally
apertured plug fitted to said barrel, said aper-
ture placing the hollow of said holder in
45 communication with the interior of said
barrel, and a valve for the pen aperture.

10. A pen point for a fountain pen pro-
vided with a filling aperture, a hollow holder
50 provided with a compressible bag, and a bag
compressing member adapted to also serve
as a valve for said filling aperture.

11. A pen point for a fountain pen pro-
vided with a filling aperture, a hollow holder
55 provided with a compressible bag, and a bag
compressing member adapted to also serve
as a valve for said filling aperture, said pen
having valve seat projections flanking said
aperture.
